UNITED STATES PATENT OFFICE.

CHARLES I. STOLOFF, OF NEW YORK, N. Y.

DENTAL MANDREL.

Application filed April 11, 1925. Serial No. 22,313.

This invention relates to dental appliances, and relates more particularly to an improved dental mandrel.

The present invention has particular reference to the provision of an improved dental mandrel of the type comprising a rotatable shaft having a work member such as a grinding or polishing implement detachably carried by one end of the shaft and 10 designed and constructed to be receivable by the mouth of the patient, which work member is detachably secured to the shaft by means of a securing device which is threadedly receivable by the end of the shaft, and 15 which is adjusted to hold the work member in secured relation onto and against the end of the shaft. In practice, a single mandrel shaft is employed with any of a variety of work members, and where the work member 20 consists of an abrasive or polishing implement, the same may be in the form of a sand paper disk, metal or carborundum disks, grinding stones, rubber caps and the like, these being interchangeably attachable 25 to the mandrel by the removal and adjustment of the securing device in accordance with the character of the work to be performed.

In mandrels of prior and known constructions, the work member is secured onto the mandrel shaft by the threaded adjustment of the securing device, the work member being held between the shaft end and the head of the securing device. In order to hold the 30 work member in fixed relation on the shaft in these prior mandrel constructions, the threaded connection between the securing device and the shaft is made such that the rotation of the work member will have a 35 tendency to engage the head of the securing device and move the latter into tightened condition. However, it has been universally found in operation and use of these mandrels that for one reason or another the securing devices are not properly engaged by 40 the rotatable work member, and that the work member is not held in fixed relation on the shaft, but rotates relatively thereto. This relative rotation is a source of great 45 annoyance to the user, since the grinding, cutting or polishing action of the implement is rendered less efficient, the work member sometimes working loose to an extent which 50 prevents its operation altogether, this necessitating removal of the mandrel from the

mouth of the patient and objectionable adjustment by the operating dentist.

To overcome these objections and to improve upon the operation of these mandrels, it has been suggested to insert various elements between the head of the securing device and the work member, such as flat or 60 spring washers and the like, for the purpose of assisting the automatic adjustment of the securing device during use of the 65 mandrel. These flat or spring washers, however, have not materially improved the operation of the mandrel, and especially so after the work members have been in service for a moderate period of time. The spring 70 washer inserted between the head of the securing device and the work member has proved ineffective in use for a number of reasons, prime among which are that the engaging surface between the spring washer 75 and the work member is small and hence insufficient, and that such spring washer exerts an axial push between the head of the securing device and the work member which in large measure prevents by counteraction 80 the axial adjustment of the securing device. I have also found that another cause for the ineffective engagement between the parts to produce the desired adjustment is that the 85 rotation of the work member is so rapid as to be insufficient to overcome the inertia of the securing device against tightening movement.

A prime desideratum of my present invention therefore comprehends the provision of an improved mandrel construction in which the above-mentioned disadvantages inherent in prior structures are effectively overcome, and in which a compensating means is provided and arranged between the work member and the head of the securing device 90 designed and constructed to eliminate the disadvantages inherent in spring washer inserts and to produce a means which automatically effects the tightening of the securing device and thus compensates for all 95 looseness and consequent relative movement between the work member and the shaft in an effective and workable fashion.

To the accomplishment of the foregoing 105 and such other objects as will hereinafter appear, my invention consists in the elements and their relation one to the other, as hereinafter particularly described and sought to be defined in the claims; reference being had to the accompanying drawings which show 110

preferred embodiments of my invention, and in which:

Fig. 1 is a view of a dental mandrel showing my improvements applied thereto,

5 Fig. 2 is a view of the same showing the parts in detached relation, and

Fig. 3 is a view of a modification.

Referring now more in detail to the drawings, the dental mandrel comprises a rotatable shaft 10 having an enlarged head 11 at one end thereof, the said shaft being provided at such end with an axially tapped bore 12 for receiving a correspondingly threaded portion 13 of a securing device 15 generally designated as 14 and having a head 15, a work member 16 such as a grinding or polishing wheel or disk being removably attachable to the mandrel and secured between the enlarged head 11 of the shaft 20 and the head 15 of the securing device 14.

With this construction of the mandrel, the work member 16, which may be a polishing, separating or grinding implement such as a sand paper disk, carborundum disk or grinding stone, etc., is removably attachable to the mandrel shaft and is secured in fixed position on the shaft by means of the adjustment of the securing device 14. As has been explained, the work member 16 works itself loose in practice, with a consequent annoyance both to patient and dentist due to the improper functioning thereof; and to overcome the above-mentioned objections and disadvantages inherent in known mandrel constructions, my present invention comprises the introduction of means between the outer face 16^a of the work member and the contiguous end of the head 15 of the securing device which functions to automatically tighten the securing device onto the mandrel shaft 10 and thus automatically adjust and compensate for any tendency towards relative movement between the work member 16 and the mandrel shaft 10.

45 In the preferred construction of the invention as shown in Figs. 1 and 2 of the drawings, the means for effecting the automatic tightening of the securing device comprises an element 17 arranged to engage the outer face 16^a of the work member and located between the same and the head 15 of the securing device and a resilient member 18 connecting the said element 17 and the head 15 of the securing device, the connection being such as to permit yieldable relative rotation between the element 17 and the said head of the securing device.

More specifically in the preferred embodiment the engaging element 17 is flat or disk-shaped so as to provide for maximum frictional surface contact between the same and the outer face 16^a of the work member, and the resilient member 18 preferably comprises a helical spring having one end 18^b fixedly connected to the flat-shaped washer

element 17 and having the other end 18^b fixedly attached to the securing device head 15. I have found, however, that the attachment of only one end of the spring is sufficient to accomplish the desired end, but a fixed attachment of both ends of the helical spring 18 materially improves the function of the device. In the preferred construction as shown in the embodiment of the invention in Figs. 1 and 2 of the drawings, the head 14 of the securing device is made cup-shaped or hollow so that the helical spring 18 may be appropriately concealed and housed by the head, as clearly shown in Fig. 1 of the drawings.

By the provision of this described construction, I have found that the outer face 16^a of the work member 16 always engages the contiguous face of the washer element 17, the same being urged axially into engagement with the work member by the helical spring 18, and that the frictional engagement is more than ample to act upon the head 15 of the securing device through the intermediation of the spring 18 to cause the said securing device to adjust itself into tightened condition. The spring 18 preferably is comparatively light, so that it will have no tendency by its axial action to oppose the rotation of the securing device into tightened position, the spring 18 functioning more in the nature of a connecting means between the washer 17 and the head of the securing device which permits that partial and yieldable relative rotation between the washer 17 and the head of the securing device sufficient to overcome the inertia tendencies of the latter. The construction provided, therefore, functions to effect the automatic take-up of the adjusting screw with certainty.

Referring now to Fig. 3 of the drawings, I show a modification of the invention in which the mandrel comprises a shaft 10' having the enlarged head 11' and axial bore receiving a securing device 14' having a construction similar to that heretofore described, and including a threaded shank 13' and a hollow or cup-shaped head 15', a work member such as a sand paper disk 16' being receivable between the parts of the mandrel. In this form of my invention, however, I eliminate the washer 17 and employ the helical spring 18' which is attached to the head 15' as the means for producing the desired results, the said helical spring being flattened at its bottom so as to engage the outer face of the work member 16, the said flattened bottom being the equivalent of the washer 17 and comprising the element which engages the outer face of the work member. In this construction the results are not accomplished as effectively as in the embodiment shown in Figs. 1 and 2 of the drawings, but I have found that the frictional

engagement combined with the torsional action of the spring on the head of the securing device is sufficient to produce that rotative movement of the securing device 5 desired for automatically tightening the work member.

While I have shown my invention in the preferred forms, it will be understood that many changes and modifications may be 10 made in the structure disclosed without departing from the spirit of the invention, defined in the following claims.

I claim:

1. A mandrel comprising a rotatable shaft having an axially tapped bore at one end thereof, a work member detachably carried by the shaft at said end, a securing device having a shank portion threadedly receivable by said bore and a head portion associated with the work member to secure the same on the shaft and against the said end thereof, and means for holding the work member in secured relation on the shaft and for automatically tightening the securing device and thus compensating for looseness and consequent relative movement between the work member and the shaft, said means comprising an element engaging the outer face of the work member and arranged between the same and the head of the securing device and a resilient member having torsional and axial resilient components connecting the said element and the said head, the connection being such as to permit yieldable relative rotation between the said element and the said head of the securing device.

2. A mandrel comprising a rotatable shaft having an axially tapped bore at one end thereof, a work member detachably carried by the shaft at said end, a securing device having a shank portion threadedly receivable by said bore and a head portion associated with the work member to secure the same on the shaft and against the said end thereof, and means for holding the work member in secured relation on the shaft and for automatically tightening the securing device and thus compensating for looseness and consequent relative movement between the work member and the shaft, said means comprising a flat-shaped element engaging the outer face of the work member and arranged between the same and the head of the securing device and a resilient member fixedly connected at opposite ends to the said element and the said head, the connection being such as to permit partial and yieldable relative rotation between the said element and the said head of the securing device.

3. A mandrel comprising a rotatable shaft having an axially tapped bore at one end thereof, a work member detachably carried 60 by the shaft at said end, a securing device

having a shank portion threadedly receivable by said bore and a head portion associated with the work member to secure the same on the shaft and against the said end thereof, and means for holding the work member in secured relation on the shaft and for automatically tightening the securing device and thus compensating for looseness and consequent relative movement between the work member and the shaft, said means 70 comprising an element engaging the outer face of the work member and arranged between the same and the head of the securing device and a helical spring connecting the said element and the said head.

4. A mandrel comprising a rotatable shaft having an axially tapped bore at one end thereof, a work member detachably carried by the shaft at said end, a securing device having a shank portion threadedly receivable by said bore and a cup-shaped head portion associated with the work member to secure the same on the shaft and against the said end thereof, and means for holding the work member in secured relation on the shaft and for automatically tightening the securing device and thus compensating for looseness and consequent relative movement between the work member and the shaft, said means comprising an element engaging the outer face of the work member and arranged between the same and the head of the securing device and a helical spring connecting the said element and the said cup-shaped head and arranged to be concealed within and housed by the said head.

5. A mandrel comprising a rotatable shaft having an axially tapped bore at one end thereof, a work member detachably carried by the shaft at said end, a securing device having a shank portion threadedly receivable by said bore and a cup-shaped head portion associated with the work member to secure the same on the shaft and against the said end thereof, and means for holding the work member in secured relation on the shaft and for automatically tightening the securing device and thus compensating for looseness and consequent relative movement between the work member and the shaft, said means comprising a flat washer element engaging the outer face of the work member and arranged between the same and the head of the securing device and a helical spring fixedly connected at opposite ends to the said element and the said cup-shaped head and arranged to be concealed within and housed by the said head, the connection being such as to permit partial and yieldable relative rotation between the said element and the head of the securing device.

Signed at New York city, in the county of New York and State of New York this 10th day of April A. D. 1925.

CHARLES I. STOLOFF.
